CLAIM

The ornamental design of a marble game playing board,
substantially as shown and described.

DESCRIPTION

FIG. 1 is a perspective front view of a marble game
playing board showing my design;

FIG. 2 is a front elevational view thereof;

FIG. 3 is a rear elevational view thereof;

FIG. 4 is a leftside elevational view thereof;

FIG. 5 is a rightside elevational view thereof;

FIG. 6 is a top plan view thereof;

FIG. 7 is a bottom view thereof; and

FIG. 8 is a pictorial view showing an animal figure in a
lower position.
